Primary Examiner — Cynthia R Underwood(74) *Attorney, Agent, or Firm* — Ann K. Gallagher(57) **CLAIM**

The ornamental design for a hook, as shown and described.

DESCRIPTION

FIG. 1 is a perspective view of a first embodiment of a hook of the present disclosure;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the hook of the present disclosure shown in an environment of use;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

(Continued)

The broken lines depict portions of the hook that form no part of the claim and an environment of use.

1 Claim, 6 Drawing Sheets
